UNITED STATES PATENT OFFICE.

CHARLES A. WOOLSEY, OF MINNEAPOLIS, MINNESOTA.

BOX.

1,269,242.

Specification of Letters Patent. Patented June 11, 1918.

Application filed February 17, 1913, Serial No. 748,902. Renewed November 15, 1915. Serial No. 61,685.

To all whom it may concern:

Be it known that I, CHARLES A. WOOLSEY, a citizen of the United States, residing at Minneapolis, Hennepin county, Minnesota, 5 % Northern Express Company, have invented certain new and useful Improvements in Boxes, of which the following is a specification.

My invention relates to shipping boxes 10 and particularly to that class which are returned to the shipper when empty. This type of box must necessarily be made strong and durable and the object of my invention is to provide a reinforcing means for the 15 corners of the box which will support and strengthen the walls thereof against pressure from within or without.

A further object is to provide a box which may be made of any suitable size and with 20 wide or narrow strips in its walls, as preferred. Other objects of the invention will appear from the following detailed description.

The invention consists generally in various 25 constructions and combinations, all as hereinafter described and particularly pointed out in the claims.

In the accompanying drawings forming part of this specification,

Figure 1 is a perspective view, looking 30 toward the outside of one corner of the box, Fig. 2 is a similar view, looking toward the corner of the box on the inside,

Fig. 3 is a vertical sectional view through 35 a corner of the box,

Fig. 4 is a perspective view, looking toward the corner of the box on the outside, with one of the reinforcing plates removed,

Fig. 5 is a perspective view of the inner 40 and outer reinforcing plates, a portion of the inner plate being broken away,

Fig. 6 is a perspective view of the inner plate,

Fig. 7 is a perspective view, showing a 45 portion of the reinforcing or protective means at the bottom of the box,

Fig. 8 is a perspective view, showing the reinforced covering, which is substantially the same in construction as the angle plates 50 in Fig. 5, divided longitudinally through the angle therein.

In the drawing, 2, 3 and 4 represent the slats composing the side and end walls and bottom of the box. These walls are shown 55 as composed of narrow slats, or wider strips or boards may be used, if preferred. I have

only shown one corner of the box, but it will be understood that the other corners are constructed in substantially the same way. 5 represents an angle plate of sheet 60 metal, preferably galvanized, adapted to fit the corner of the box on the outside and cover the meeting ends of the side and end walls. From the longitudinal edges of this plate lips or ears 6 are punched and are bent 65 inwardly to a position at right angles substantially to the plane of the walls, and between the adjacent ears the ends of the slats 2 and 3 are inserted, with the ears projecting inwardly between the edges of 70 adjacent slats, the ears being preferably of sufficient length to extend from the outer to the inner surface of each slat.

I prefer to arrange the slats as indicated in Fig. 4, in which one slat in a wall extends 75 into the angle plate and contacts therewith, while the adjoining slat next beneath in the same wall abuts against the adjacent slat of the other wall, so that an alternate construction is provided which serves to increase 80 the strength of the corner. At the top and bottom the plate 5 is provided with inwardly turned ears 7 and holes 8 and 9 are provided in these ears, the holes 8 being in line with similar holes provided in the 85 ears 6. On the inner side of the angle formed at the corner of the box is a second angle plate 10 having outwardly turned ears 11 and 12 formed thereon and provided with holes 13 and 14 corresponding to those 90 described. When these plates are assembled, one on the inside and the other on the outside of the box, the ears formed thereon lap by one another, as indicated in Fig. 5, and the holes in the ears of one plate will 95 register with the corresponding holes in the ears of the other plate. Through these holes and transversely through holes in the slats, lacing wires 15 are inserted, having their ends bent inwardly and inserted into the 100 holes 9 and 14 at the ends of the reinforcing plates, as indicated in Fig. 3. These lacing wires, passing through the holes in the ears and through the slats, will secure them firmly together and the end of each slat 105 will be inclosed with a metal covering or jacket with a double thickness at the edges of each slat, and the corner will be securely braced and strengthened against pressure from the outside or inside of the box. Gen- 110 erally, boxes having only an outer guard or protection at the corner will split or

break when subjected to extreme outside pressure, as there is nothing to brace the inner surface of the wall, but with the construction herein shown and described, each 5 slat is completely inclosed at the end, and not only inclosed, but is laced and locked to the adjacent slat, and consequently pressure on one slat will be to a considerable degree resisted and braced by the other slats 10 of the same wall.

Between each slat is a double thickness formed by the overlapping ears, and the lacing wires have comparatively long bearing in these ears and are so securely braced 15 by them that splitting of a slat is practically impossible.

At the corner formed by the intersection of the ends of the bottom slats and an upright wall, I prefer to provide a reinforcing means which may be formed independently of the corner plates or be a continuation thereof, as preferred. In this case I have illustrated the parts formed separately. The plate 16 is folded to completely inclose 25 the lower slat 3 of the side wall and has a flange 17 which extends under the end of the bottom slats 4 covering the joint between them and the slat 3. A flange 18 is provided on the opposite corresponding edge of 30 the plate 16 and is spaced from the flange 17 and parallel substantially therewith and overlaps the ends of the slats 4 on the inside of the box. From the longitudinal edges of these parallel flanges 17 and 18 ears 19 35 and 20 are punched, and arranged to lap by one another and are provided with holes 21 therein which register when the ears are bent into their proper relation with one another.

40 The plate 16 is preferably provided at the ends thereof with an inwardly turned flange 22 having an ear 23 and a corresponding ear 24 is formed on said plate on the opposite side of the angle. The flange 22 has a 45 hole 25 therein, into which the end of the lacing wire 26 is inserted, and the flange 17 has an upwardly turned lip 27 which overlaps the flange 22 and is provided with holes to register with the holes 21 and 25 therein. 50 This lip 27 serves to reinforce the corner of the box at the bottom and coöperates with the flange 22 and the corner plate to further strengthen the box at the meeting point of the slats. I have shown this horizontal corner 55 plate, formed independently of the upright corner plate, but I may prefer to make them of one piece of metal. This construction, however would be obvious and illustration herein does not seem to be necessary. In 60 the event of making the reinforcing plates of one piece of metal, there would be only one thickness of metal instead of several, as shown in the drawings.

In Fig. 8 I have shown a reinforcing 65 plate which corresponds substantially to a

section of the corner plate formed by dividing it longitudinally through the angle of the corner. This plate consists of an outer wall 28 and parallel flanges 29 between which the ends of the slats are inserted, said 70 flanges having inwardly projecting ears 30 pressed or punched therefrom and extending between the longitudinal edges of the slats, and ears 31 formed at the ends of the flanges with lacing wires 32 inserted 75 through holes in said ears and transversely through the slats, thereby locking them securely together. In this construction the ends of the slats will be entirely inclosed and protected, and separation of the slats will be 80 prevented, even though the box may be subjected to a sufficient strain or blow to split the slats. It will be noted in Fig. 3 that the lacing wires extend through the upright 85 and horizontal corners of the box from top to bottom and end to end thereof and form practically a continuous means for holding the slats or boards comprising the walls and bottom of the box securely together, while the ends of the slats ordinarily exposed to splitting or breaking, are entirely covered and concealed by the metal reinforcing plates. I have shown the box with close walls, but obviously the alternate slats 90 may be omitted to form a crate-like construction without varying the form of the protecting plates or the means for locking them and the slats together.

These reinforcing plates may be applied to other articles, as well as for reinforcing corners of boxes, and hence I do not confine myself to the uses of the invention herein shown and described.

I claim as my invention:—

1. A box having walls composed of slats 105 arranged one above another, angle plates fitting the corner of the box on the inside and outside thereof and having ears punched from their longitudinal edges, the ears of the inner plate lapping and co-inciding substantially with the ears of the outer plate, the ears of both plates being seated on the longitudinal edges of the slats, the ends of said slats being inclosed and concealed by said plates and ears, and lacing wires passing through said slats transversely and through the ears of said inner and outer plates and securing said ears and said slats together.

2. A box comprising a bottom and a wall 120 having a slat adjacent to said bottom, a metallic plate folded to inclose said slat and having inwardly projecting, substantially parallel flanges lapping over and concealing the joint between said slat and 125 the bottom of the box, said flanges having ears pressed therefrom to enter the bottom of the box, and a lacing wire passing through the box bottom and through the ears therein.

3. A box comprising a bottom and walls, each consisting of a series of slats placed edge to edge, an angle plate fitting the corner of the box on the outside thereof and having ears punched from its vertical, longitudinal edges, said ears projecting inwardly between the slats of said walls and seated on the longitudinal edges of said slats, a horizontal plate folded to inclose the lower slat 10 of one of said walls and having sockets for the ends of the bottom slats, said horizontal plate having an end portion adapted to receive the lower end of said angle plate and provided with ears to register with the ears 15 of said angle plate, and lacing wires passing vertically through said slats and ears and horizontally through said bottom slats and the sockets thereof.
4. A box comprising a bottom, and a wall 20 having a slat adjacent to said bottom, a metallic plate folded to inclose said slat and having inwardly-projecting, substantially parallel flanges lapping over and concealing the joint between said slat and 25 the bottom of the box, the slats composing the box bottom being inserted between said parallel flanges, said flanges having ears pressed therefrom to pass between said slats, said plate having a part to embrace the 30 corner of the box, and lacing wires passing through said ears and slats and through said corner embracing part.
5. A box corner reinforcement comprising a metallic angle plate fitting the corner 35 of the box on the outside and provided with ears pressed at intervals from its longitudinal edges and projecting inwardly into the space between the flanges of said plate, said ears being arranged in pairs, slats arranged 40 one above another, forming the walls of the box and having their ends inserted between the ears of a pair and between the adjacent pairs of ears, the longitudinal edges of said slats forming seats for the ears, and flexible 45 lacing means passing downwardly through said slats and ears and binding them together.
6. A box corner reinforcement comprising
- a metallic angle plate fitting the corner of the box on the outside and provided with 50 ears pressed at intervals from its longitudinal edges and projecting inwardly into the space between the flanges of said plate, said ears being arranged in pairs, slats arranged one above another and forming the walls of 55 the box and having their ends inserted between the ears of a pair and between the adjacent pairs of ears, the longitudinal edges of said slats forming seats for said ears and corresponding substantially in width to the 60 length of said ears, and lacing wires passing downwardly through said slats and ears and binding them together.
7. A box having walls composed of slats arranged one above another, angle plates 65 fitting the corner of the box on the inside and outside thereof and having ears punched from their longitudinal edges and projecting into the joints between abutting slats, said ears being arranged in pairs and said 70 slats having their ends inserted between the ears of a pair and between the adjacent pairs of ears, the ears of the inner plate registering with the corresponding ears of the outer plate, and lacing wires passing 75 transversely through said slats and through said ears between the abutting edges of said slats and binding them together.
8. A box having walls composed of slats arranged one above another, angle plates 80 fitting the corner of the box on the inside and outside thereof and having ears punched therefrom and projecting into the joints between abutting slats, the ears of the inner plate registering with the corresponding 85 ears of the outer plate, and lacing wires passing transversely through said slats and through said ears between the abutting edges of said slats and binding them together.

In witness whereof, I have hereunto set 90 my hand this 11th day of February, 1913.

CHARLES A. WOOLSEY.
